UNITED STATES PATENT OFFICE.

AUGUST W. NELSON, OF SPOKANE, WASHINGTON.

HEAD-REST.

1,271,205.

Specification of Letters Patent.

Patented July 2, 1918.

Application filed June 10, 1916. Serial No. 102,978.

To all whom it may concern:

Be it known that I, AUGUST W. NELSON, a citizen of the United States, residing at Spokane, in the county of Spokane and State 5 of Washington, have invented new and useful Improvements in Head-Rests, of which the following is a specification.

This invention relates to improvements in headrests and has to do more particularly 10 with a device of this kind for out-of-doors use, the device of my invention being particularly adapted to rest upon bare or solid ground.

In parks and other places of like nature 15 it is a common practice to lie down upon the grass, especially in hot weather, and without some form of head support it is impossible for a person to assume anything like a comfortable position even while lying on 20 the back or face upward.

It is the object of this invention to provide a head rest which is readily portable and easily collapsible and otherwise adapted to comfortably support the head at the desired elevation while the user is lying on the 25 ground. Because of the different positions which the body may assume, or which the user may take, it is highly desirable to render a device of this character adjustable so 30 that it will support the head of the user not only at the desired elevation but also at the preferred inclination.

It is a feature of this invention to provide a head rest having a supporting frame of 35 such novel form that the frame will normally be unstable to support itself in an upright position on the ground and which will therefore be readily tiltable into any desired inclination from the horizontal or into 40 a horizontal position, means being provided which is preferably adjustable for engaging the frame and the ground to hold the frame in the desired position.

By reason of the fact that it is desirable 45 to leave portions of the head free for normal respiration, it is a feature of this invention to provide a head supporting member of skeleton form so that practically all parts of the head and neck will be freely exposed 50 to the air thereby avoiding objectionable perspiration.

Other features and objects of the invention will be more fully described in connection with the accompanying drawing and 55 will be more particularly pointed out in and by the appended claims.

In the drawing:

Figure 1 is a view in end elevation showing the device of my invention as it would appear resting upon relatively rough or uneven soil.

Fig. 2 is a front elevation looking from the right of Fig. 1.

Fig. 3 is a plan view.

Fig. 4 is a detail view of one section folded up.

Fig. 5 is a view of a portion of the head supporting member illustrating one manner of attachment to the frame.

Like characters of reference designate 70 similar parts throughout the different figures of the drawing.

As illustrated, my invention includes a frame composed of end sections indicated as a whole at 1-2 and which end sections are 75 of identical construction. Said end sections may be adjustable toward and from each other in accordance with the length of head rest desired, and in carrying out this feature, I provide a connecting bar or rod formed of 80 two sections, 3 and 4. Section 3 is rigidly connected with end frame section 1 and section 4 is rigidly connected with end frame section 2. The rod section 3 telescopes the tubular section 4 for some considerable distance in all adjustments. Means is provided for locking said sections in adjusted positions and I have shown such means in the form of a spring strip 5, anchored to section 4 at 6 and provided on its free end with a 85 pin adapted to enter registering openings in sections 3 and 4 corresponding to the adjustment desired.

End section 1 includes a yoke which may be formed of relatively stiff wire, the yoke 95 being given two turns about section 3, as indicated at 8 and being secured thereto in any desired manner. From the point of anchorage 8, the yoke comprises oppositely extending limbs 9 and 10 diverging upwardly from the point of anchorage 8. At 11 and 12 said limbs are bent upwardly as indicated at 13 and 14, the terminal ends being bent to form hooks 15 and 16, opening to the left of Fig. 2, or in other words, endwise outwardly of 100 the frame.

Head member supporting rods 17 and 18 are provided on their lower ends with eyes 19 and 20 which are adapted to be inserted along the limbs 9 and 10 into the position 110 shown in Fig. 4, when the frame is to be collapsed, or in the position shown in Fig.

1 when the frame is extended. Thus in Fig. 1, the eyes connect with the limbs 9 and 10 and intermediate portions are supported by the open hooks against movement endwise 5 inwardly. The wire of which the rods 17 and 18 and also the yokes are made is not so stiff but what it will yield somewhat to the weight of the head so that the head support will not be rigid and unyielding. The 10 upper ends of the supports are threaded and are provided with nuts 22 for a purpose which will presently appear.

Now it will be seen that the frame converges toward its base and that the frame 15 would be unstable to support itself in an upright position or in a position at an inclination to the horizontal. In other words, the rod sections 3 and 4 and the end yokes would not alone support the frame in the position 20 shown in Fig. 1.

I will now describe a feature of novelty or structure the purpose of which is to stabilize or support the frame.

The rods 17 have their upper ends 23 bent 25 horizontally. Near the outer ends are pivoted at 24 supporting rods 25 having sharpened ends 26 adapted to enter the ground. Each rod 25 has a ground engaging stop or abutment 27, which is suitably 30 flared to present a considerable lower area to the ground. Said stop is provided with a nut 28 which is adjustable on the rod 25 by means of threads 29. The upper end of each rod 25, as indicated at 30, is provided 35 with a head member holding end, the purpose of which will presently appear.

In Fig. 3, I have shown my improved head supporting member which comprises a plurality of strips of fabric 31 and 32 40 which are shown transversely disposed with respect to each other to form a member of skeleton construction. I may connect the strips at their junctures or intersections by stitching the same, as indicated at 33. 45 Along one margin, or as indicated on strip 34, I dispose elongated neck pads 35 and 36, on the upper and lower faces. This expedient relieves the user from any uncomfortable feeling about the neck which would 50 result if the margin were unprotected by a pad. Transversely of the head member, I dispose a dividing pad 37 so that if the head rest is used by two persons, this dividing pad will serve to maintain the users' 55 heads in separated relation. The reason why two neck pads 35 and 36 are provided is to enable a single user to reverse the position of the head supporting member, end to end, from the position shown in Fig. 2, to 60 dispose the dividing pad 37, below, as indicated in dotted lines at 38. At the corners of the head member I provide apertures to fit over the ends of rods 18 and also over the ends of supporting rods 25. If desired, 65 the rods 18 may be threaded and the head

member may rest upon the adjustable nuts 22, of the rods 18. Thus the front margin where the neck pads are located may be adjustable and may be lowered with respect to the rear margin. Inasmuch as this adjustment would involve slack, because of the converging relation of the rods, I preferably provide the head member with openings 39, in addition to the corner openings, in cases where downward adjustment is desired. 75 Thus it will be seen that the pad portion of the head member may be adjusted at different elevations, thereby making the head member broadly adjustable on the frame, and in addition the frame may be tilted by 80 adjusting the stops 27.

In order to protect the head of the user from the rays of the sun I provide a sun shade which may be a sheet of canvas or like fabric 40. The canvas 40 is supported on 85 the ends of shade rods 41 which are shown provided with spring clips 42 adapted to be detachably connected with rods 18. Shade rods 43 are also provided with spring clips 44 which may be attached to supporting 90 rods 17.

It will be seen that I have provided an endwise extensible head rest which may be utilized with head supporting members of different lengths. Furthermore, my improved head rest is readily collapsible in 95 separate sections, as indicated in Fig. 4, so that it may be carried in the pocket of the user.

A special feature of novelty consists in 100 mounting the forward corners on the head member supporting rods 18 and the rearward corners on the adjusting rods 25. Thus the pressure on the adjusting rods will render the same effective in anchoring 105 the stand in adjusted position.

It is believed that the novelty and utility of my invention will be clearly understood from the foregoing description, and while I have herein shown and described one specific form of my invention I do not wish to be limited thereto except for such limitations as the claims may import. 110

I claim:

1. In an out-of-doors headrest, a frame 115 adapted to rest upon the ground, and a head supporting member mounted on said frame and composed of angularly arranged strips of fabric, an elongated neck pad extending along one margin of said member, and a 120 dividing pad extending transversely of the length of said member, substantially as described.

2. In a headrest, a skeleton frame provided with end sections each comprising a 125 yoke and the limbs of said yoke having terminal hooks opening endwise outwardly with respect to said frame, a pair of supporting rods for each end section and each supporting rod having its lower end loosely 130

connected with a portion of its respective yoke, an intermediate portion seated in one of said hooks, and a head supporting member connected to the upper end of said rod, 5 substantially as described.

3. In a headrest, a frame adapted to rest upon the ground, a head supporting member mounted on said frame and provided with an elongated neck pad extending along 10 one margin, and a dividing pad extending transversely of the length of said head supporting member, substantially as described.

4. In a headrest, a frame adapted to rest upon the ground, and a head supporting 15 member mounted on said frame composed of flexible material, elongated neck pads on opposite sides of one margin of said head supporting member, and a dividing pad extending transversely of the length of said mem- 20 ber on one side thereof, substantially as described.

5. In a headrest, a skeleton frame pro-

vided with end sections each comprising a yoke and the limbs of said yoke having terminal hooks opening endwise outwardly 25 with respect to said frames, a pair of supporting rods for each end section and a supporting rod having its lower end loosely connected with a portion of its respective yoke and an intermediate portion seated 30 in one of said hooks, a head supporting member connected to the upper end of said rod, shade supporting rods one secured to each of said aforementioned rods between the point of attachment of said head supporting member of said hooks, and a shade mounted upon the upper ends of said shade supporting rod in overhanging relation with respect to said head supporting member, substantially as described. 35

In testimony that I claim the foregoing as my own, I hereby affix my signature.

AUGUST W. NELSON.
